UNITED STATES PATENT OFFICE.

CHARLES J. WOHLANDER, OF SAN FRANCISCO, CALIFORNIA, ASSIGNOR OF ONE-HALF
TO BENJAMIN ARMER, OF SAN FRANCISCO, CALIFORNIA.

SANITARY ATTACHMENT FOR TOILET-BOWLS AND THE LIKE.

1,091,265.

Specification of Letters Patent.

Patented Mar. 24, 1914.

Application filed April 23, 1913. Serial No. 763,145.

To all whom it may concern:

Be it known that I, CHARLES J. WOHLANDER, a citizen of the United States, residing at San Francisco, in the county of San Francisco and State of California, have invented new and useful Improvements in Sanitary Attachments for Toilet-Bowls and the like, of which the following is a specification.

10 The object of the present invention is to provide simple and efficient means for disinfecting and deodorizing toilet bowls, particularly of that class in which the water used for flushing the bowl is first delivered 15 to a conduit formed in the upper edge of the bowl and is then discharged into the bowl through small holes formed in the lower part of said conduit.

20 In the accompanying drawing, Figure 1 is a plan view of a toilet bowl equipped with my invention; Fig. 2 is an enlarged vertical section of an upper portion of the bowl, showing my invention in end view thereon; Fig. 3 is a plan view of the main 25 portion of my device, the lid being raised; Fig. 4 is a longitudinal section thereof; Fig. 5 is a transverse section on the line 5—5 of Fig. 4.

20 Referring to the drawing, 1 indicates a toilet bowl, in the upper edge of which is formed a conduit 2 extending around the bowl, into which the water for flushing the bowl is delivered, and from which it is discharged by holes 3 through the lower 25 portion of said conduit. Extending beneath the seat 4 and over the edge of one side of said bowl, preferably slightly in front, is a hanger 6, the bottom of the outer portion of which is thickened, as shown at 7, and 0 is formed with a threaded hole, through which passes a screw 8 having thereon a loose head 9, which can be employed to turn the screw inward, but which is inoperative to turn the screw outward. A screw having 5 such a head is in common use and need not here be further specified. Said screw is provided with a foot 11, which bears against the outer side of the bowl, and is formed of rubber to prevent cracking the bowl. The lower end of the inner portion of the hanger is secured by screws 12 to the back of the upper portion 13 of a receptacle. Said upper portion 13 is secured to the lower portion 14 of the receptacle by screws 16

the ends of the upper portion 13 and lower portion 14 respectively. The lower portion 14 is formed with a long, narrow mouth 19, and the hanger 6 is of such a form that, when secured in position on the edge of 60 the bowl, said mouth will be immediately under the holes 3 discharging from the conduit 2, said mouth being of such length as to receive the water discharged through several of said holes. The water entering 65 said mouth flows to the lower portion of said receptacle 14 and can escape therefrom only through discharge holes 21 formed in the bottom of said lower portion. Before escaping by said holes 21, the water comes in 70 contact with balls 22 of solid antiseptic material which are supported above the bottom of said lower portions 14 of the receptacles by a perforated tray or trough 23 supported thereon by lugs 24 extending from 75 its end. In order to supply said trough with said antiseptic balls, a hinged lid 26 of said upper portion 13 is first raised, and then the antiseptic balls are passed downward, one at a time into a chamber 27 formed 80 in the upper portion 13 of the receptacle, from which they drop upon the trough 23. The balls are of such character that the water coming in contact therewith acts as a carrier of the disinfectant and deodorizing ingredients contained in the balls. The upper portion 13 of the receptacle is likewise formed with a second chamber 28 separated from the lower portion 14 of the receptacle by a bottom or partition 29, in 90 which chamber is inserted a suitably molded block of material giving out, by evaporation, an agreeable perfume, thus counteracting, if necessary, the odor of the disinfectant, and other noxious odors. The walls of these 95 chambers 27, 28 are formed with apertures 31, permitting the vapor of the antiseptic balls and the perfumed blocks to escape therefrom.

It is understood that I by no means limit 100 my invention to its use as shown and described herein, but claim the same for any other uses for which it may be found advantageous.

I claim:

105 In combination with an open-topped bowl or vessel, the edge of said top being formed with a perforated conduit for discharging water into said receptacle, a receptacle having a long, narrow mouth, means for se- 110

2
curing said receptacle adjacent to the top of said vessel in a position so that the mouth receives the water discharged from several of the perforations in said conduit, a perforated trough in said receptacle to which the water received by said mouth can flow, said receptacle being formed with escape holes for the water, and the upper portion of said receptacle being formed with two chambers, one communicating with said trough, and the other partitioned therefrom,

the walls of said chambers having apertures, and means for closing the top of said chambers.

In testimony whereof I have hereunto set 15 my hand in the presence of two subscribing witnesses.

CHARLES J. WOHLANDER.
